US0D1050054S

(12) **United States Design Patent** (10) **Patent No.:** **US D1,050,054 S**
(45) **Date of Patent:** **** Nov. 5, 2024**

(54) **BACKUP POWER SWITCHING DEVICE**

(71) Applicant: **Zhejiang Futian RV Technology CO., Ltd.**, Zhejiang (CN)

(72) Inventor: **Peng Su**, Zhejiang (CN)

(73) Assignee: **Zhejiang Futian RV Technology CO., Ltd.**, Hangzhou (CN)

(*) Notice: Patent file contains an affidavit/declaration under 37 CFR 1.130(b).

(**) Term: **15 Years**

(21) Appl. No.: **29/850,223**

(22) Filed: **Aug. 18, 2022**

(30) **Foreign Application Priority Data**

Aug. 5, 2022 (CN) 202230509384.5

CLAIM

The ornamental design for a backup power switching device as shown and described.

DESCRIPTION

FIG. 1 is a top, front and left side perspective view of a backup power switching device showing my new design; FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

(Continued)

The broken lines in the drawings illustrate portions of the backup power switching device which form no part of the claimed design.

1 Claim, 8 Drawing Sheets
